(57) **CLAIM**

The ornamental design for a handset, as shown and described.

DESCRIPTION

FIG. 1 is a top plan view of a first embodiment of a handset showing our new design;

FIG. 2 is a perspective view of the handset in one in use position;

FIG. 3 is a front view of the handset in an in use position;

FIG. 4 is a front view of the handset;

FIG. 5 is a perspective front view of the handset;

FIG. 6 is a perspective front view of the handset in an in use position;

FIG. 7 is a perspective view of the handset in an in use position;

FIG. 8 is a perspective view of the handset in an in use position;

FIG. 9 is a left side of the handset;

FIG. 10 is a right side view of the handset;

FIG. 11 is a bottom plan view of a second embodiment of a handset showing our new design;

FIG. 12 is a right side view thereof;

FIG. 13 is a front view thereof;

FIG. 14 is a right side view thereof;

FIG. 15 is top plan view thereof;

FIG. 16 is a rear view thereof;

FIG. 17 is a perspective front view thereof;

FIG. 18 is a perspective rear view thereof;

FIG. 19 is a perspective front view of the handset of FIGS. 11-18 in an in use position;

FIG. 20 is a perspective view of the handset of FIGS. 11-18 in an in use position;

FIG. 21 is a perspective left view of the handset of FIGS. 11-18 in an in use position;

FIG. 22 is a perspective right view of the handset of FIGS. 11-18 in an in use position; and

FIG. 23 is a front view of the handset of FIGS. 11-18 in an in use position.
